CAR WASHING ATTACHMENT FOR HOSES

Porter M. Shey, Detroit, Mich.

Application October 20, 1950, Serial No. 191,130

5 Claims. (Cl. 15—129)

1

This invention relates to improvements in attachments for standard hoses and standard nozzles.

An object of this invention is to provide an improved washing head for a standard hose and nozzle, which washing head is characterized by a unique water distribution assembly for the mop carried thereby and improved means of fastening the attachment to the nozzle and hose.

Ancillary objects and features of novelty will become apparent in following the description of the illustrated forms of the invention.

In the drawings:

Figure 1 is a longitudinal sectional view of the device;

Figure 2 is a fragmentary elevational view showing a part of the means of holding the attachment to a standard hose and nozzle;

Figure 3 is a fragmentary bottom view of the device of Figure 1;

Figure 4 is a transverse sectional view taken substantially on the line 4—4 of Figure 1 and in the direction of the arrows;

Figure 5 is a fragmentary elevational view of another form of the invention, portions being broken away in section to illustrate internal detail;

Figure 6 is an elevational view in reduced scale of the device of Figure 5;

Figure 7 is a transverse sectional view in an enlarged scale taken substantially on the line 7—7 of Figure 6 and in the direction of the arrows;

Figure 8 is a perspective view of a means of fastening the hose to the device, and;

Figure 9 is a perspective view of the cutoff valve forming a part of the invention.

Attention is first invited primarily to Figures 1—4. There is a standard garden hose 10 with a standard nozzle 12 thereon. The garden hose is provided with a male coupling member 14 at one end which is threaded into the female coupling member or collar 16 of the nozzle 12. This equipment is standard.

A tube 20 is provided with a fixed collar 22 at one end into which an insert or adapter 24 is fitted and held in place by friction. This insert is employed so that different sizes of nozzles may be accommodated. There is a resilient liner 25 in the bore of the insert to frictionally engage the collar 16.

A gasket or washer 26 is interposed between the front surface of the insert 24 and the wall formed at the juncture of the collar 22 and the main body of the tube 20. This is to prevent leakage between the insert and the collar 22.

2

A plurality of bendable tongues 28 are fixed to the insert 24 and adapted to overlie the innermost surface of the collar 16, thereby holding it fixed to the nozzle 12. The locking action of the liner 25 will usually be sufficient to hold the nozzle in place, but the tongues 28 may be used in lieu thereof or in addition to the liner.

At the forward end of the tube 20 there is an extension 30 which is disposed at an angle with respect to the longitudinal axis of the remainder of the tube 20. This extension defines a liquid chamber 32 which is arranged to receive water from the nozzle 12. An aperture 34 is provided in the extension 30 and there is a grommet 36 located in this aperture.

A closure 38 for the opening 34 is connected to the tube 20 by means of a spring loaded hinge assembly 40, the hinge assembly constantly pressing the closure 38 in the aperture 34 closing position and the spring of the spring hinge assembly 40 opposing the opening movement of the closure 38. It will be noted from inspection of Figure 1 that the lower end of the closure partially overlies the water deflector or skirt 42 which is connected to the neck 44 by means of the flange 46 on the outside surface of the neck 44, fitting into a suitable groove in the skirt 42.

A water diffuser 48 is carried by the bracket 50 which is fixed to the closure 38 and when the closure is in the aperture 34 closing position, the stream of liquid issuing from the nozzle 12 is diffused due to the axial alignment of the diffuser 48 and the nozzle 12. However, when the closure is in the opened condition the diffuser 48 is moved thereby moving it so that it will not interfere with the stream issuing from the nozzle 12.

There is a means for operating the closure 38 located on the saddle bearing 52. This means consists of a lever 54 pivoted to the saddle bearing 52 and a link 56 which is connected to the lever and also to a bracket 58, which is fixed to the closure 38. The guide 60, which is secured by standard means to the collar 22, is employed to prevent undesired movement of the link 56.

There is a soap container 62 carried by one wall of the tube 20 and located in advance of the nozzle 12. This container 62 is provided with a spring closing valve 64 which is arranged for manual operation.

An action clamp 66 which includes pivoted arms 68 and 70, is used to assist in firmly holding the insert and hence the nozzle and hose in place within the tube 20. This action clamp includes the arms 68 and 70 which are pivoted at 65 their outer ends to the collar 22 and a cam type

locking lever 72 which is pivoted to the opposite ends of the arms 68 and 70. The cams on the lever 72 are arranged to contact the insert 24, pressing and holding it against the gasket 26 very tightly.

The saddle bearing 52 is connected to the sleeve 22 by means of the arm 74. This saddle bearing is provided with rolled edges constituting guides or bearings 76 and 78 through which the arms 80 and 82 are adapted to slide. These arms, cooperating with the cradle 84 constitute a means of supporting the hose 10 at a distance from the tube 20. The cradle is made of two or more wire members connected by braces, the wire members being hinged to one of the wire members 82 and adapted to connect to the other wire member 80 through the medium of the bent end portions 86 and 88 of the cradle which frictionally contact the wire member 80.

There is a means for holding the mop 90 in communication with the bore of the neck 44. This means comprises a tubular, internally threaded coupling 92 which constitutes a head for the mop 90. Midway between its ends, the coupling is formed with an internal, annular shoulder. A neck extension 96 having an enlarged, externally threaded, upper end 94 is threaded into the coupling 92 so that the upper end thereof seats on the coupling shoulder and the lower end 98 thereof projects below the coupling into the center of the mop 90. As will be noted, the lower end 98 of the extension 96 is conical and provided with a plurality of apertures for diffusing spray into the central portion of the mop. After the extension 96 is inserted, the coupling is then threaded onto the lower end of the neck 44.

A plurality of apertures 100 are formed in the neck 44 intermediate its upper and lower ends. These apertures empty some water into the water deflector 42 so that it is directed on the outside surface of the mop. Other water enters the inside of the mop 90 through the diffuser 96.

In operation after the water begins to flow through the nozzle 12 it passes through the apertures 100 in neck 44 and is deflected to the outside of the mop 90. Other water passes through the apertured diffuser 96 to wet the inside of the mop.

If additional water is desired on the mop the closure 38 is opened a slight amount, the water then being directed on the outer surface of the deflector 42 and on the mop. If water is desired in advance of the working surface, the closure 38 is opened slightly more. When it is desired to have substantially all of the water pass directly through the opening 34, the closure 38 is opened the full amount. To use soap during the cleaning operations, the valve 64 is manually actuated.

Attention is now invited to Figures 5-9 wherein there is a cleaning head 104 connected with the outer end of the tube 106. This cleaning head is identical to the previously described one. The differentiating features between this modification and the modification of Figures 1-4 are the means of holding the standard garden hose 108 and nozzle 110 in place within the tube 106, and the means of supporting the hose 108 any place remote from the washing head.

The tube 106 is provided with an elongated collar 112 which has an opened outer end. At the inner end of this collar there is an insert 114 or a thickness of material, against which a part of the nozzle 110 abuts.

A two-piece bearing or insert 116 is located in the collar 112 and is adapted to hold the hose 108 fixed in place. This insert 116 consists of a first part 118 and the second part 120, each of these parts having reduced ends around which standard clamps 122 and 124 are placed. Resilient adapters 126 and 128 are placed around the hose 108 and between the parts 118 and 120 of the insert 116. The adapters may be selected from various sizes of a number of adapters so as to amply provide for variations in diameter of hoses 108.

The upper part 130 of the collar 112 extends rearwardly and is adapted to embrace a part of the hose 108, constituting a saddle bearing. The closure operating lever 132 is pivoted to this saddle bearing.

Various means may be used to hold the hose 108 in place within the saddle bearing. For example, the strap 134, threaded in slots in the saddle bearing may be used as disclosed in Figure 5. This type of construction is inexpensive and yet serves the purpose well.

In order that a selected length of hose behind these washing heads may be supported, a telescopic holder 138 is connected to the saddle bearing. This holder is substantially semi-circular in cross section and has a standard latch 140 at one end thereof arranged to underlie the hose 108. Accordingly the holder 138 may be slid outwardly or inwardly of the saddle bearing depending upon the prerogative of the user of the device.

As disclosed in Figure 6 a shut off valve 144 may be used. This valve consists of a lever 146 which is pivotally carried by the depending brackets 148 which are connected to the shield 150. This shield is riveted or otherwise rigidly fixed to the substantially semi-cylindrical hose holder 152 which is telescopically connected with the saddle bearing 130.

The inner end of the lever 146 is provided with a bearing 153 which presses against the hose 108. Therefore by pivotal movement of the lever 146, the bore of the hose may be closed by the bearing 156 squeezing against it.

Instead of ordinary straps or latches to hold the hose 108 in a fixed position with respect to the holders 138 or 152, the device illustrated in Figure 8 may be used. This device consists of a collar 160 which is slidable over the holder 152. The collar is provided with two or more springs 162 which press against not only the holder 152 but also a part of the hose 108, thereby holding the hose in fixed position. To facilitate sliding movement and prescribe its travel the guide 166 may be used. This guide is of the simplest type of construction, consisting only of a ring which is arranged around the hose, a part of the holder 152 and a part of the saddle bearing 130.

Having described the invention, what is claimed as new is:

1. For use with a standard hose having a standard nozzle, a washing head attachment comprising a tube having means therein for releasably holding the nozzle in said tube, a mop, means for connecting said mop to said tube at the discharge end of said tube, means connected to said tube for directing water from the tube onto selected portions of said mop, a saddle bearing connected to said tube and arranged to hold a part of the hose, and a holder adapted to clampingly embrace a portion of the hose secured 70 to said saddle bearing by means of a sliding con-

nction so that selected amounts of the hose may be supported remote from said mop.

2. A washing head attachment for a nozzle, said attachment comprising a tube having a liquid chamber at one end, a neck connected to said tube and opening at one end into said chamber, said neck having lateral openings therein, a mop connected to the end of said neck opposite from that end which opens into said chamber so that water from the chamber passes into the mop, a deflector located around said lateral openings to deflect liquid therefrom on to the mop, said chamber having walls with an opening in one of the walls, said opening being positioned in the path of liquid ejected from the nozzle, a closure for said opening arranged to open selected amounts for directing liquid from the chamber in selected directions, and means including a collar connected to said tube and an adapter located in said collar for holding the nozzle in place in said tube. 20

3. A washing head attachment for a nozzle, said attachment comprising a tube having a liquid chamber at one end, a sleeve connected to said tube and opening at one end into said chamber, said sleeve having lateral openings therein, a mop connected to the end of said sleeve opposite from that end which opens into said chamber so that water from the chamber passes into the mop, a deflector located around said lateral openings to deflect liquid therefrom on to the mop, said chamber having walls with an opening in one of the walls, said opening being positioned in the path of liquid ejected from the nozzle, a closure for said opening arranged to open selected amounts for directing 25

liquid from the chamber in selected directions, means including a collar connected to said tube and an adapter located in said collar for holding the nozzle in place in said tube, a saddle bearing connected to said collar and arranged to seat upon a part of the hose, and a holder operatively connected with said saddle bearing for supporting another part of the hose.

4. The combination of claim 3 in which said holder includes an assembly which is slidably connected to said saddle bearing and which has a means for underlying the hose and holding it from separation from the holder.

5. The combination of claim 3 wherein tongues are connected to said collar and arranged to press against said adapter and hold the same fixed in said collar.
